United States Patent Office.

DEXTER SYMONDS, OF LOWELL, MASSACHUSETTS.

Letters Patent No. 70,043, dated October 22, 1867.

IMPROVEMENT IN VAPOR-BURNER.

The Schedule referred to in these Letters Patent and making part of the same.

TO ALL WHOM IT MAY CONCERN:

Be it known that I, DEXTER SYMONDS, of Lowell, in the county of Middlesex, and State of Massachusetts, have invented certain new and useful improvements in Lamps for Generating and Burning Gas, of which the following is a full, clear, and exact description, reference being had to the accompanying drawings, making part of this specification, in which is represented a vertical central section considerably enlarged.

In this invention the fluid-reservoir A is arranged on the top of a vertical tube, B, the bottom end of which screws into a metallic step, C, secured in a base, D, made of marble or other material sufficiently heavy to hold the apparatus firmly in a vertical position, or so that it will not tip over. A plug, O, provides for filling the reservoir. One or more metallic supply pipes, E, extend outward from the central tube B, and a regulating supply-cock, F, is arranged in said pipe or pipes. One end of a supporting-tube, G, screws into the outer end of the pipe E, and extends outward a short distance, and is curved downward, forming a quarter circle, then round and upward about a half circle, the end turning upward vertically, and a collar, a, secured thereto a short distance from the end. A metallic conducting pipe, b, is arranged within the tube G, and the ends of both are soldered together. A metallic conducting-wire, c, passes through the pipe b, and both ends project a little beyond the ends of the tubes. The object of this conducting-wire is to cause an even flow of fluid through the pipe b, and prevent the fluid going through in drops or irregularly. I surround the outer vertical end of the tube G with a tube, of cork, or other suitable non-conductor, f, which rests on the top of the collar a, and is held down by a nut, e, screwed on to the outer top end of the tube G. A sectional tube, I, large at the bottom end, and tapering within, fits snugly on to the insulator f, and has a vapor-chamber, d, above the insulator. The upper portion of the tube I is much smaller, and has a small interior, extending upward to within the shank of the top button g. The top end of the upper section h of the tube I has a serrated edge, and the vapor from the chamber d passes upward and over the serrated edge, and into the gas-chamber k within the bulb. A metallic wire, X, extends from the top of the aperture in the shank of the button g downward into the vapor-chamber, and its lower end is coiled or twisted, and rests in a packing of cotton or other light substance.

In using my improved lamp the cock F is turned to admit a small quantity of fluid through the pipe b into the lower part of the vapor-chamber d. A flame is held in contact with the bulb, which forms the gas-chamber k and the button g. Heat passes down the button and its shank and the wire x to the fluid-saturated cotton in the vapor-chamber d, causing vapor to rise and pass over the serrated top edge of the tube h into the gas-chamber k, where gas is formed by the heat applied to the bulb. The gas passes out at small holes around the under side of the bulb and ignites. The flame first named may then be removed, and the cock F gradually opened to admit a full supply of fluid through the pipe b around the wire c. The heat passing down the wire x generates vapor quite rapidly, and the pressure of such vapor and the gas within the bulb prevents the fluid flowing too rapidly into the vapor-chamber d, even though the cock F is wide open. After this lamp has been lighted it will continue to burn with a beautiful flame so long as the reservoir is kept supplied with suitable fluid, and the supply-cock kept open. Closing the supply-cock extinguishes the flame in a short time. Considerable heat passes down the tubes h and I to generate vapor in the chamber d, and the insulator f prevents the escape and loss of such heat, and without the insulator the heat passing down the tube I would pass along the supporting-tube G, and be of so little effect as to prevent or seriously retard the generating of vapor in the vapor-chamber. It will be readily seen that the space between the tubes G and b prevents the possibility of heat being conducted to the fluid within the tube b, so that volatile oils or fluids may be used in this lamp with perfect safety.

Having fully described my invention, what I claim as new, and desire to secure by Letters Patent, is—

1. A gas-generating and gas-burning lamp, constructed and arranged to operate substantially as and for the purpose specified.
2. The insulator f, arranged and applied substantially as and for the purpose set forth.
3. The arrangement of the tubes or pipes G and b, whereby the fluid is protected from the action of external heat, substantially as set forth.

DEXTER SYMONDS.
